United States Patent Office

Des. 201,494
Patented June 29, 1965

201,494

AWNING

Joseph Schlager, 2501 S. Kearney St., Denver, Colo.

Filed Apr. 16, 1964, Ser. No. 79,523

Term of patent 14 years

(Cl. D13—1)

Fig. 1

Fig. 2

Fig. 3

Fig. 4

FIGURE 1 is a front elevational view of the design of the awning, the right support shown fragmentarily for convenience of illustration only.

FIGURE 2 is a side elevational view of the awning.

FIGURE 3 is an enlarged fragmentary view of the lower left corner portion of the showing at FIG. 2.

FIGURE 4 is a fragmentary sectional view of the right end of the portion shown at FIG. 3.

I claim:

The ornamental design for an awning, as shown and described.
